WALL STRUCTURE HAVING ANCHORED
ARCHITECTURAL FACINGRichard H. Turk, Baltimore, Md., assignor to
Pemco Corporation, a corporation of Maryland

Application May 20, 1941, Serial No. 394,374

9 Claims. (Cl. 72—18)

The present invention relates to the production of porcelain enameled architectural units and shapes, and the application thereof to a carrying surface while the latter is in a plastic state, said carrying surface being adapted to thereafter harden and support said porcelain enameled unit.

It has previously been proposed to provide iron or steel sheets or tiles having a porcelain enameled exterior finish and to attach the same to interior supporting surfaces such as bathrooms, kitchens, and the like, but such architectural shapes have been provided with screws, bolts, clips and the like adapted to be fastened to studing, metal moulding, or similar parts. Aside from the rather complicated mechanical arrangements previously necessary for attaching the shape to the retaining supports, such as a wall or the like, a major difficulty has been encountered in that the large sized porcelain enameled sheets and panels exceeding, for example, 12 to 18 inches in any one direction were not sufficiently well anchored to the supporting surface so as to present a smooth exterior surface free from bulging and warping. Due to the high gloss porcelain enamel finish often employed in architectural panels and shapes, comparatively small eccentricities in the contour of the surface of the unit are greatly magnified, and as a result detract from the esthetic appeal of the tile panel or other unit. The difficulty encountered in anchoring such sheets and panels in place so that the latter present a flat plane surface has, up to the present time, resulted in a substantially negligible use, especially in the treatment of interior walls or the like, of large panels or sheets provided with a porcelain enamel finish. It is desired to point out that if the above difficulties could be surmounted, porcelain enameled sheets and tiles would become very popular in places where cleanliness and ease of cleaning are important and especially in interior decoration of bathrooms, kitchens and the like, it being further pointed out that the porcelain enamel finish is available in many colors and can be adapted to produce a great many decorative effects.

It has been ascertained that the solution of the problem resides in providing the porcelain enameled panels or other shaped members with projecting members and embedding the latter in the supporting medium while the latter is in a plastic state, said carrying medium after embedding of the projecting means hardening

around the projecting means to thereby hold the panel member rigidly in a uniform plane.

This method of application may be employed when the carrying medium is a wall provided with a coating of wet plaster. After the plaster has been applied to the wall and while the plaster is in a plastic state, the projecting members of the porcelain enameled sheets or tiles are pressed into the wet plaster coating, said coating upon drying anchoring the sheets or panel members rigidly in a uniform plane and preventing the sheets from bulging and warping. It is to be noted that this method of application not only provides the wall or other supporting surface with a firmly adherent flat architectural shape such as a sheet or tile, but, as stated, eliminates the necessity of complicated mechanical arrangements for attaching the shape to the carrying medium. Further, in employing the method heretofore used, it was necessary to accurately space the porcelain enameled sheets or the like on the surface of the supporting material in order to properly attach the porcelain enameled sheets and tiles to the carrying surface by means of bolts, screws, clips and the like.

It has further been ascertained that the interior surface of the panel member and its projecting members were subject to the rusting and corroding influence of the supporting medium and that this could be prevented by providing all of the surfaces exposed to the supporting medium such as a plaster surface with a coating of porcelain enamel, the latter reacting with the metal surfaces to key itself thereto.

The present invention will be illustrated in connection with the accompanying drawings in which:

Figure 1 is a plan view of the rear surface of a porcelain enameled panel provided with anchoring means;

Figure 2 is a detail section showing a portion of the panel of Figure 1 embedded in plaster;

Figure 3 is a sectional view of a panel provided with a modified anchoring means;

Figure 4 is a back plan view of a panel provided with wire loop anchoring members;

Figure 5 is a horizontal section taken on line 5—5 of Figure 4;

Figure 6 is a back plan view of a panel provided with a plurality of cut out continuous anchoring angles;

Figure 7 is a horizontal section taken on line 7—7 of Figure 6;

Figure 8 is a vertical section taken on line 8—8 of Figure 7;

Figure 9 is a sectional view of a porcelain enameled pre-formed tile provided with loops spot welded to tile indentation members; and

Figure 10 is a sectional view of a porcelain enameled pre-formed tile provided with a screen anchoring unit.

As shown in Figure 1, the iron or steel panel 1 is provided with projecting anchoring members 2, having a horizontal leg 4 and a vertical leg 5, the horizontal leg of the members being spot welded to the panel 1 at 3. The stock of the panel is preferably 20 to 22 gage while the projecting angle members are preferably made of light gage enameling iron of approximately 24 gage. The angle irons may be of any suitable width but preferably $\frac{1}{2}$ to 1 inch so that each angle member may be spot welded to the panel 1 in a single operation. The length of the extending leg 5 of each angle is slightly less than the thickness of the carrying medium as, for example, a plaster coating P to which the finished panel or sheet is secured. The plaster coating P is carried by the supporting member S.

The anchoring members 3 are symmetrically secured to the back surface 6 of the panel member, the spacing being such as to provide adequate support and anchorage to the panel. However, an excessive number of anchoring members are not necessary. As shown in Figure 1, the legs are spaced 4 inches apart. The spacing may be varied in accordance with the character of the supporting medium, the character of the panel and its anchorage members, and the size of the panel.

After the anchoring members have been secured to the panel 1, the article is provided with a coating of a vitreous enamel such as porcelain enamel. The article is chemically cleaned to remove grease and dirt and then subjected to an acid pickle to remove iron oxide and scale. Thereafter, a base coat 7 is applied to the front surface 8 of the panel 1, the back surface 6 thereof, and to all the exposed surfaces of the anchoring members 2. The coating is fired in place at the usual ground coat firing temperature which may be around 1500° to 1600° F. whereby the coating is caused to fuse, vitrify, and react with the base material to adhere firmly to the metal of the panel.

After the ground coat enamel has been fired in place, one or more vitreous or porcelain enamel cover coats 9 of any desired color or combination of colors and patterns may be applied to the ground coat 7 on the front face of the panel, and this exterior vitreous-forming coating may be fired at the usual temperature at which cover coats are fired, which may be around 1400° to 1500° F. to produce the final vitreous or porcelain enamel finish. The so produced article is now ready for erection. The vertical legs 5 of the anchoring members 3 are embedded in the plaster 10 while the latter is in a plastic soft and unhardened state, said plaster being adapted to harden by exposure to the air or by exposure to any medium which will accelerate the hardening of the plaster.

As is well known, lime plaster is used for the plastering of the insides of buildings and this is the preferred plastering medium which is applied to the wall to be plastered. However, any of the prior art plastering mediums may be used including calcium sulfate plasters. It is obvious that the plaster may have other ingredients mixed with it and usually said ingredients include a filler medium such as sand. The plaster

is applied in two coats, the first coat being termed the scratch coat and the second being termed the brown coat. It is desired to point out that the present invention may be used in connection with any plaster which is soft or plastic and is adapted to receive and/or have embedded therein the anchoring members of a panel provided with an exterior coating of porcelain enamel, and preferably a corrosion resisting interior coating of porcelain enamel, said plaster hardening by setting or equivalent reaction. Other materials may be substituted for the plaster, the criterion being that at the time of application of the panel members, the wall or other supporting member should have thereon a soft unhardened coating adapted to harden after the anchoring members of the panel have been pressed into the coating.

In the form of the invention shown in Figure 3, the protruding legs 11 of the anchoring member 12 are twisted to provide a satisfactory anchorage.

In the form of the invention shown in Figures 4 and 5, the rear surface 14 of the panel 13 is provided with anchorage members made by providing a wire 16 with loops 15 and spot welding the loops as at 17 to the rear surface 14 of the panel 13. A plurality of wires having a plurality of loops are desirably used, said wires and loops being placed to provide adequate support for the panel. The interior surface of the panel member and the projecting members are provided with a ground coat 18 and the exterior surface of the panel is provided with a cover coat 19.

A further modification of the invention is shown in Figures 6 to 8, inclusive. Instead of welding a series of single lugs to the back surface of the panel member, the angle iron 20 may have portions of one flange removed as by cutting out the metal to provide a series of integral lugs 21. The remaining flange 22 may be spot welded as at 23 to the inner surface 25 of the panel 24.

In the form of the invention shown in Figure 9, the panel member is provided with simulated tiles 26 adjacent to tile indentations 27. Secured to the back surface 28 of the tile indentations 27 are a plurality of wires 30 provided with loops 31, the bottoms of which are spot welded as at 29 to the surface 28. The tile indentations 27 may be spaced sufficiently from the plaster surface to provide an air space between the tile and the plaster surface, said air space acting as a heat insulating medium. If no insulating effect is desired, the tile indentations 27 may rest on the plaster surface or be slightly embedded therein so that the entire surface of the tile member 26 is in firm contact with the exterior surface of the plaster P or equivalent medium secured to the support S.

In the form of the invention shown in Figure 10, the tile indentations 33 of the tiles 32 have a wire screen 36 spot welded at 35 to the rear surface of the tile indentations.

In the form of the invention shown in Figures 6 to 10, inclusive, the interior surface of the panel or tile member and the members projecting therefrom to form anchorage means are provided with a corrosion inhibiting coating of a vitreous or porcelain enamel. After dipping the article with its anchorage means in the ground coat porcelain enamel composition, the ground coat is fired at the usual ground coat firing temperature whereby the coating is caused to fuse, vitrify on cooling, and react with the base material to adhere firmly to the metal of the panel or the tile. The exterior

surface of the article shown in Figures 6 to 10, inclusive, may be provided with an exterior fired porcelain enamel coating of the character hereinbefore set forth.

Any of the forms of the invention shown in Figures 6 to 10, inclusive, may be applied to a supporting surface having a plastic coating, as, for example, plaster or the like, while the plaster is in a soft and unhardened state. Upon hardening, the article will be rigidly held in the uniform plane whereby warping and bulging of the panel and distortion of the exterior porcelain enamel coating carried by the panel is prevented.

Instead of spot welding anchorage means onto the panel plate, the panel may be shaped as by stamping to provide integral anchorage members of various shapes.

The term "iron or sheet steel" as used in the specification is intended to cover not only the high quality low metalloid content steel sheet commonly used as a base for porcelain enamel, but also any iron or steel base capable of being porcelain enameled, said base containing substantial proportions of alloying constituents, as, for example, nickel, chromium, tantalum, molybdenum, zirconium, and the like. While steel sheet is the metal base generally used for the application of architectural porcelain enamels, the present invention is in no way limited to porcelain enameled architectural units having such sheet steel base, but may also apply to porcelain enameled architectural units using any other suitable metal as a base, as, for example, copper, copper alloys, aluminum, aluminum alloys, nickel, nickel alloys, and similar metal bases or alloys thereof.

While in the specification the application of the corrosion resisting inner lining and the exterior porcelain enamel coating is described as using two firing steps, the enamel coatings may be brought to a fusion and vitrification by a single firing step.

Having thus described the invention, what is claimed as new and desired to be secured to by Letters Patent is:

1. In combination, a supporting member, an in situ hardened-coating thereon, and a panel member having an exterior coating of porcelain enamel, anchorage means secured to and holding said panel closely adjacent the exterior surface of the hardened coating, said anchorage means comprising a wire having base portions extending adjacent to the inner surface of the panel member, loop wire portions intermediate said base portions and extending outwardly therefrom, said portions being formed of upwardly extending leg members, the interior surfaces of which are in face to face contact, spot welds at the juncture of the loop leg members and base portions uniting said anchorage means with said panel and preventing the spreading of said loop portions, said loop portions extending into said hardened coating so that said panel member is held rigidly in a uniform plane whereby warping and bulging of the panel and distortion of the exterior enamel coating is prevented.

2. In combination, a supporting member, an in situ hardened-coating thereon, and a panel member having an exterior surface of porcelain enamel, a portion of said panel member being spaced from the supporting member to provide an insulating pocket, other portions of said panel being held by anchorage means secured to the panel in firm, rigid contact with the exterior surface of said hardened coating, said anchorage means comprising a wire having base portions

spot welded to the inner surface of the panel member, and loop portions extending from said base portions into said in situ hardened-coating so that said panel member is held rigidly in a uniform plane whereby warping and bulging of the panel and distortion of the exterior enamel coating is prevented.

3. In combination, a supporting member, an in situ hardened-coating thereon, and a panel member having an exterior surface of porcelain enamel, projecting members extending from the rear of said panel member and in firm, rigid contact with the exterior surface of said hardened coating, the portion of the panel member between said projecting members being spaced and depressed from the exterior surface of the supporting member to provide an insulating pocket, anchorage means secured to said projecting members, said anchorage means comprising a wire having base portions spot welded to said projecting members, and loop portions extending from said base portions into said in situ hardened-coating so that said panel member is held rigidly in a uniform plane whereby warping and bulging of the panel and distortion of the exterior enamel coating is prevented.

4. In combination, a supporting member, an in situ hardened-coating thereon, and a panel member having an exterior coating of porcelain enamel, a portion of said panel member being spaced from the supporting member to provide an insulating pocket, other portions of said panel being held by anchorage means secured to the panel in firm, rigid contact with the exterior surface of said hardened coating, said anchorage means comprising a wire having base portions extending adjacent to the inner surface of the panel member, loop portions intermediate said base portions and extending outwardly therefrom, spot welds at the juncture of the loop and base portions uniting said anchorage means with said panel and preventing the spreading of said loop portions, said loop portions extending into said hardened coating so that said panel member is held rigidly in a uniform plane whereby warping and bulging of the panel and distortion of the exterior enamel coating is prevented.

5. In combination, a supporting member, an in situ hardened-coating thereon, and a panel member having an exterior coating of porcelain enamel, projecting members extending from the rear of said panel member and in firm, rigid contact with the exterior surface of said hardened coating, the portion of the panel member between said projecting members being spaced and depressed from the exterior surface of the supporting member to provide an insulating pocket, anchorage means secured to said panel, said anchorage means comprising a wire having base portions extending adjacent to the inner surface of the panel member, loop portions intermediate said base portions and extending outwardly therefrom, spot welds at the juncture of the loop and base portions uniting said anchorage means with said panel and preventing the spreading of said loop portions, said loop portions extending into said hardened coating so that said panel member is held rigidly in a uniform plane whereby warping and bulging of the panel and distortion of the exterior enamel coating is prevented.

6. In combination, a supporting member, an in situ hardened-coating thereon, and a panel member carrying a porcelain enamel coating on its exterior surface, projecting members extending from the rear of said panel member, the portions

of the panel member between said projecting members being spaced from the exterior surface of the supporting member to provide insulating pockets, anchorage means secured to said projecting members, said anchorage means comprising an elongated base portion disposed adjacent to the rear of said panel, and a plurality of means projecting from said base portion into said hardened coating, so that said panel member is rigidly held in a uniform plane whereby warping and bulging of the panel and distortion of the exterior enamel coating is prevented.

7. In combination, a supporting member, an in situ hardened-coating thereon, and a panel member having an exterior surface of porcelain enamel, anchoring means for anchoring and holding said panel member rigidly in a uniform plane and closely adjacent the exterior surface of said hardened coating, whereby warping and bulging

of the panel and distortion of the exterior enamel coating is prevented, said anchorage means comprising a wire having base portions and loop portions integral therewith and extending upwardly therefrom, said loop portions being formed of upwardly extending leg members, the interior surfaces of which are in face to face contact, and provided with means at the lower extremities of the leg members to prevent the spreading thereof, said means also uniting the anchorage base portions to the panel member.

8. The unit of claim 1 wherein the anchorage means is provided with a corrosion-resisting coating of porcelain enamel.

9. The unit of claim 7 in which the anchorage means is provided with a corrosion-resisting coating of porcelain enamel.
